SHUTTLE DRIVE MECHANISM

Bertram J. Goldsmith, Neshanic, N. J., assignor
to Royal Swan, Inc., Dover, Del.

Application April 10, 1947, Serial No. 740,685

6 Claims. (Cl. 139—336)

1

This invention relates to new and useful improvements in mechanisms for driving shuttles in looms.

An object of the invention is to provide a simple, efficient, strong, and durable device in which the stoppage due to breaking or jamming of the parts is reduced to a minimum.

A further object is to provide a simple, efficient device in which the drive motor of the mechanism is instantly cut off when undue strains or loads are put upon the parts and wherein the amount of load to operate the cut-off means can be adjusted at will.

Further and more specific objects, features, and advantages will more clearly appear from a consideration of the specification hereinafter set forth especially when taken in connection with the accompanying drawings which illustrate a present preferred form which the invention may assume and which form part of the specification.

Previous forms of looms have employed shuttle driving devices including straps and flexible elements therein which wore out and required frequent replacement and which often suddenly broke and caused stoppage of the operation. In this invention the drive mechanism is more positive in that it does not include such elements and consequently is not likely to wear as rapidly and to result in unexpected breakages.

The invention further includes a driving device in which there is a drive means and means for controlling it together with load-sensitive means associated with the shuttle mechanism to cut off the drive means when the load varies or becomes abnormal.

The invention also includes means to adjust the load-sensitive device so that the cut-off of the drive may occur at different values of loads applied to the drive mechanism.

More particular details of the novel and useful combination of elements employed will be set forth in the following specification and drawings which show and describe a present preferred form which the invention may assume.

In the drawings:

Fig. 1 is an elevation of the drive mechanism looking at the end of the loom;

Fig. 2 is a plan view thereof;

Fig. 3 is a partial enlarged elevation of the control switch;

Fig. 4 is a vertical section through the switch taken on the line 4—4 of Fig. 1;

Fig. 5 is a vertical section taken on the line 5—5 of Fig. 2; and,

2

Fig. 6 is a vertical section taken on the line 6—6 of Fig. 2.

Referring now merely to the specific structure representing the present preferred form of the invention shown in the drawings, it is apparent that there is provided a supporting frame member 10 having a flat top shelf 11 on which certain of the operating parts are adjustably disposed. This frame or bracket 10 may be preferably attached to the side of the end frame of the looms in any suitable manner (not shown) since it forms no part of the invention.

The drive mechanism is activated from a power shaft 12 connected to a drive motor. On this shaft 12 is a gear 13 meshing with a pinion 14 on a shaft 15 on which there is a worm meshing with a worm gear 17 on a shaft 18 one end of which carries a cam plate 19 one face of which is cut with a cam groove 20 of any desired configuration. In this groove or cam slot 20 there lies a cam follower 21 rotatably disposed on the end of a rock arm 22, the other end of which is fast on a shaft 23 which extends laterally and horizontally away from the cam plate 19 and is rocked by the rocking of the arm 22. This shaft 23 passes through a bearing sleeve 24. This sleeve is supported on the outer end of a plate 25 which has rear spaced bosses 26 disposed respectively inside and adjacent bosses 27 and are pivotally related thereto by means of pins 28. The bosses 27 are disposed at opposite rear sides of a plate 29 which has corner bolts 30 extending through slots 31 in the plate 11 on which the plate 29 rests. By these slots and bolts the plate 29 is adjusted on the plate or shelf 11 so that the disposition of the shaft 23 and its related parts may be easily determined. By reason of this construction it will be clear that the shaft 23 can be raised and lowered since it is supported on an element which is pivoted at the pins 28. To restrain somewhat and in a predetermined manner this movement, the plate 29 has a medial elevated portion having slots 33 through which bolts 34 extend and by means of which a spring plate 35 can be adjusted by moving the bolts 34 along in the slots 33 and adjusting them as desired. Cross bars 34' extend across the top and bottom of the spring plate 35 and grip it between them. This engagement is adjusted at the ends of bars 34' by means of the bolts 34 and nuts 36 associated therewith and disposed both above and below the ends of the bars 34' as shown. Thus by adjusting the bolts 34 in the slots 33 the fixed point of the spring 35 can be varied and thus the resistance of the spring to

flexion be also varied. The other end of the spring 35 is held against the bottom of a lug 38 formed on the bearing sleeve 24 by means of another cross bar 36' extending across beneath the plate 35 the ends of which bar 36' being firmly gripped by means of bolts 37 in a manner similar to the action on the cross bars 34' above mentioned. Therefore this simple means enables the resistance of spring 35 to be varied at will by merely sliding the bolts along in the slots 33 and then tightening them up as desired.

At the left end of the shaft 23 as viewed in Fig. 1, there are attached thereto fixed dependent arms 39 spaced apart thereon, the lower ends of which are bored to receive a drive rod 40 which is preferably rotatable in roller bearings disposed in said bores, the rod 40 extending between the arms 39. The shuttles (not shown) are operated in the usual fashion by association with a pair of spaced upper and lower rack bars 41 and 42. The right ends of these rack bars are connected respectively to bracket plates 43 and 44 connected respectively to the upper and lower ends of a slotted plate 45 having a vertical slot 46 therein. Extending rearwardly from this plate 45 are upper and lower flange bars 47 and 48 between which extend vertically a pair of spaced rollers 49 one of which is shown in Fig. 1, the other lying immediately back of it. These rollers are spaced apart and receive between them the drive rod 40 above mentioned and the space between the rollers is substantially the same as the diameter of the rod 40. Thus the driving motion of the rod 40 back and forth in one line and the back and forth motion of the rollers 49 on and with their supporting bracket plates 43 and 44 in a transverse direction is achieved with a minimum of friction and resistance since all the engaging parts, namely the rollers 49 and the rod 40 are independently rotatable.

If, in the operation of the loom, the rack bars 41 and 42, which are reciprocating rapidly, become jammed in moving one way or the other, there would be considerable damage done if the drive motor could not be stopped at once and automatically as soon as the jam occurred, or as soon as too great a load was placed upon the drive mechanism. This quick stopping or disconnection of the motor is made possible by the following mechanism:

Attached to the front face of the lug 38 on the bearing sleeve 24 is a U-shaped plate 50 in the respective legs of which are adjusted screws 51 with their ends extending into the space between the legs of the plate. Disposed between the ends of the screws are spring contact members 52 normally spaced apart and provided with insulation 53 on their sides adjacent the ends of the screws. These spring members 52 are insulatingly mounted on a plate 54 fastened to the front end of the plate 23 above mentioned. As the U-plate 50 moves up or down, one or the other screw will urge its respective spring element against the other to make contact therebetween as at 55. These elements are connected in any suitable manner (not shown) to a relay which will, when energized, act to open the circuit of the drive motor and stop the mechanism. The movement of the plate 50 up and down is caused by the increase of the load on the device due to a jamming of the parts or to other causes. This increased load will cause the bearing sleeve 24 to be rocked up or down, against the resistance of the adjusted spring 35, depending upon the

direction in which the rack bars are moving when this load increase takes place.

In the operation of the device, the movement of the motor is transmitted through the above mechanism to rock the shaft 23 and oscillate the drive rod 40 and thus reciprocate the rack bars. In normal operation and under normal load, the spring 35 has been adjusted to keep the bearing sleeve in the normal axial position but the instant the load increases above the determined value, as when a jam occurs, this sleeve will tend to move up or down and will cause a closing of the circuit to stop the motor. Thus it is apparent that I have provided in this particular form a simple, efficient, durable, and positive mechanism which will operate the racks indefinitely with much less wear and tear and with less development of lost motion in the parts and with less tendency to breakage. The device is also provided with a simple mechanism for automatically stopping the motor the instant the above mentioned load conditions arise.

While the invention has been described in detail and with respect to a present preferred form which the invention may assume, it is not to be limited to such details and form, since many changes and modifications may be made in the invention without departing from the spirit and scope of the invention in its broadest aspects. Hence it is desired to cover any and all forms and modifications of the invention which may come within the language or scope of any one or more of the appended claims.

What I claim as my invention, is:

1. In a device of the class described, an oscillatable shaft, a bearing sleeve in which it is disposed, a dependent arm on said shaft, a shuttle rack bar, a shuttle drive rod on said arm and associated with said rack to move it back and forth, a pivoted plate supporting said sleeve, a spring adjustably associated with said sleeve and tending to hold it in a normal axial line, a switch member on said sleeve, a second and fixed switch member associated therewith, movement of said sleeve from normal position causing a closure of said switch members, as and for the purposes specified.

2. In a device of the class described, a pair of spaced shuttle rack bars, a frame connecting adjacent ends thereof, a pair of spaced rollers on said frame, a rotatable shuttle drive rod extending between said rollers, an oscillating shaft from which said rod depends, a bearing sleeve in which said shaft is disposed, a pivoted plate on which said sleeve is supported to permit movement of the sleeve transverse to its axis, and spring means engaging said sleeve and tending to restrain it in a normal axial position.

3. In a device of the class described, a pair of spaced shuttle rack bars, a frame connecting adjacent ends thereof, a pair of spaced rollers on said frame, a rotatable shuttle drive rod extending between said rollers, an oscillatable shaft from which said rod depends, a bearing sleeve in which said shaft is disposed, a pivoted plate on which said sleeve is supported to permit movement of the sleeve transverse to its axis, spring means adjustably engaging said sleeve and tending to restrain it in a normal axial position, circuit closing means on said sleeve, and movable therewith, fixed circuit closing means associated therewith and adapted to be closed when the sleeve moves in either direction from the normal position.

4. In a device of the class described, a turnable

shaft, a dependent arm connected to said shaft and a reciprocable driven member connected to said arm, a pivoted support for said shaft, resilient means tending to hold the support with the shaft in a normal position, said support adapted to swing around its pivot point when the load on the shaft exceeds a determined amount.

5. In a device of the class described, a turnable shaft, a dependent arm connected to said shaft and a reciprocable driven member connected to said arm, a pivoted support for said shaft, spring means engaging the support and tending to hold the support with the shaft in a normal axial position, said support adapted to swing around its pivot point when the load on the shaft exceeds a predetermined amount, and control means associated with the support and operated by the support when the support moves from its normal position.

6. In a device of the class described, an oscillating shaft, a pivoted support on which said shaft is mounted, a shuttle rack bar, a shuttle drive rod dependent from said shaft and associated with said rack bar to move the same back

and forth, means for resiliently mounting said support to permit movement of the shaft around the pivot point of the support under abnormal loads but maintaining the shaft in a normal axial position under normal loads thereon, and a control switch element associated with the support to be closed by the movement of the support from a normal position under abnormal shaft loads.
